UNITED STATES PATENT OFFICE.

GEORGE A. DOBYNE AND STEPHEN A. DOBYNE, OF ST. LOUIS, MISSOURI, ASSIGNEES TO CHAMPION SHOE MACHINERY COMPANY, OF ST. LOUIS, MISSOURI, A CORPORATION OF MISSOURI.

THREAD-CONTROLLING MECHANISM FOR WAX-THREAD LEATHER-SEWING MACHINES.

1,198,627.

Specification of Letters Patent. Patented Sept. 19, 1916.

Application filed December 6, 1912. Serial No. 735,212.

To all whom it may concern:

Be it known that we, GEORGE A. DOBYNE and STEPHEN A. DOBYNE, both citizens of the United States, and residing at St. Louis, in the State of Missouri, have invented certain new and useful Improvements in Thread-Controlling Mechanism for Wax-Thread Leather-Sewing Machines, of which the following is a specification.

10 This invention relates to wax thread leather sewing machines and more particularly to thread controlling mechanism therefor.

There are at present two general types 15 of thread controlling mechanisms. One of these types is provided with a thread-lock or clamp for locking or holding the thread against movement while the stitch is being set; it is therefore necessary to provide 20 means for accurately measuring the thread required for forming the stitches. The other type is provided with a slip tension device, and the take-up takes up and sets the stitch against the yielding tension of this device.

25 After the stitch is set the take-up operates to draw the thread for the next stitch through the slip tension device, the thread being drawn by the surplus movement of the take-up. The thread measuring means of

30 the first type is complicated and must be extremely accurate so as to accurately measure the thread according to the thickness of the work, and this type does not take care of all the conditions encountered in sewing ma-

35 terial such as a shoe sole, where the length of the stitch must vary. On the other hand the type employing a slip tension is open to the objection that the take-up is liable to "steal" thread from the supply and through 40 the tension so that the required accuracy is not obtained.

In wax thread leather sewing machines, more especially those of the lock-stitch type, a large loop of waxed thread is drawn back 45 and forth through the work. The take-up must therefore have a long stroke, and in high speed machines this take-up must operate at a high linear speed. When the loop of the needle thread, after passing over the

shuttle, is taken up and set by the take-up 50 there is considerable resistance offered to the free movement of the waxed thread which resistance must be overcome. The needle thread must be started by the take-up, the loop of waxed thread must be drawn 55 down to the face of the work, and this loop must be drawn into the work. Now it has been found that the amount of resistance to be overcome and therefore the amount of pull required to start the waxed needle 60 thread is considerable. It has also been found that when the take-up starts to move back on its take-up stroke the high speed at which this take-up operates in high speed machines is liable to cause a 65 lashing of the thread. These resistances to the free movement of the needle thread are liable to cause the thread to be drawn from the supply and through the slip tension before the stitch is set so that the stitch will 70 be set imperfectly and ununiformly. It is objectionable to make the slip tension too tight as this will cause the thread to cut through the material and is also liable to break the thread.

75 The objects of this invention therefore are to construct a wax thread controlling mechanism of simple form which will set the stitches uniformly and accurately, and which will prevent the pulling of the waxed 80 needle thread from the supply except when this thread is to be drawn for the next stitch.

Further objects will appear from the detail description taken in connection with 85 the accompanying drawings, in which:

Figure 1 is a front elevation of a machine embodying this invention, Fig. 2 is a side elevation, Fig. 3 is a detail view showing the parts in a different position, 90 Fig. 4 is a view illustrating the operation of the machine, and Fig. 5 is a section on the line 5—5 Fig. 2.

We have found that if the waxed needle thread is locked or held against movement 95 until after the take-up has started the thread, and until the loop is drawn nearly to the face of the work, that the actual set-

ting of the stitch can be accurately performed against a yielding tension. In accordance with this invention therefore the thread is locked or held against movement 5 while it is being taken up by the take-up, but is held under a yielding tension while the stitch is being set and while the thread is being drawn for the next stitch. The thread is locked against movement until 10 after the take-up has started to draw the needle thread from the shuttle, and preferably until the needle thread loop is discharged from the shuttle and is drawn nearly to the face of the work. The thread 15 is thereafter unlocked and is only held by a yielding tension, which tension is however of sufficient strength to permit the stitch to be set properly.

Referring to the accompanying drawings 20 which illustrate an outsole sewing machine 9 designates a machine head having a main drive shaft 10 mounted thereon provided with cam wheels 12, 13 and 14. A work support or table 15 is mounted on the head and 25 has coöperating with it a presser-foot 16. The stitch forming mechanism comprising an awl 17, a curved hook needle 18, a looper 19 and a shuttle 20, is of usual construction and may be substantially as shown in Patent No. 473,870, dated April 26, 1892.

The cam wheel 14 is provided with a cam groove 11 coöperating with a cam roll 21 on an arm 22 mounted on a rock shaft 23, which rock shaft has an arm 24 connected 35 by a link 25 with the arm 26 of a take-up shaft 27 extending across the machine. The shaft 27 has rigidly mounted thereon a take-up lever 28 provided with the usual thread engaging roll.

40 A shaft or stud 29 extends laterally from the machine head and has loosely mounted thereon a wheel 30 provided with V-shaped grooves 31 and 32. A washer or plate 33 on the shaft is held against the wheel 30 by 45 means of a spring 34 mounted on the shaft, and the tension of this spring can be adjusted by nuts 35. A lever 36 pivoted at 37 on the machine head is provided with a brake shoe 38 adapted to engage the groove 32, and a spring 39 bearing against the lever 36 normally tends to hold the brake shoe in 50 engagement with the wheel 30. A cam lug 40 on the take-up lever 28 engages with a cam roll 41 on the lever 36 so as to move the shoe 38 out of engagement with the wheel 30. An auxiliary tension device 42 pivoted 55 on the machine head is normally moved in the direction of the arrow by means of a light spring as shown, and the downward movement of this tension device is limited by coöperating lugs 43 and 44 on the auxiliary tension and the machine head respectively. This auxiliary tension is of well known construction and its function is well

known, namely, to take up the slack in the 65 needle thread.

The needle thread passes from a wax pot 100 around the wheel 30 and in the groove 31 therein, over the auxiliary tension, back under the take-up, and then to the stitch forming devices. During the operation of the machine the cam 14 will through its connections operate to oscillate the take-up shaft 27 and move the take-up lever up and down. When the take-up lever is up the lug 75 40 will be out of engagement with the cam roll 41 so that the spring 39 is free to throw the brake shoe 38 into engagement with the wheel 30 and hold or lock this wheel and therefore the needle thread wrapped around 80 the wheel against movement. As the take-up reaches the lower limit of its take-up stroke the lug 40 will engage the cam roll 41 and move the brake shoe out of the groove 85 32. The wheel 30 will then be unlocked so that the wheel and the thread will be only held frictionally by the washer 33 under the tension of the spring 34. The needle thread will therefore be locked against movement during the first part of the take-up stroke 90 of the take-up lever but will be only yielding held against movement during the last part of the take-up stroke.

The mechanism is so constructed and adjusted that the needle thread 51 will be 95 locked against movement until the loop 53 of the needle thread has passed entirely off of the shuttle and is nearly drawn to the face of the work 50 as shown in Figs. 3 and 4. In Fig. 3 the parts are in such a position that the lug 40 is just in engagement with the cam roll 41 and a further downward movement of the take-up lever will cause this lug to move the brake shoe 38 out of the groove 32. After the needle thread is taken 100 up and the loop 53 is drawn nearly down to the work as shown in Figs. 3 and 4 the brake shoe is released so that the needle thread will not be under the yielding tension caused by the spring 34. The take-up will 105 now operate to draw the loop 53 into the work carrying with it the shuttle thread 52 so as to set the stitch against a yielding tension. The take-up will then operate to draw from the supply and through the tension the 110 thread for the next stitch. In Fig. 2 the parts are in position with the take-up at the lower limit of its take-up stroke, with the 115 stitch fully set and the thread for the next stitch drawn from the supply.

120 During the first part of the take-up stroke of the take-up lever and while the needle take-up performs its function to take-up the thread from the shuttle, the needle thread is positively locked against movement. The 125 lashing of the thread which may be caused by the quick movement of the take-up, and the starting resistance offered by the waxed

thread and the work, will therefore not cause the thread to be drawn from the supply. The thread is positively locked against movement when the take-up starts the 5 thread, and this positive lock is maintained until the loop of needle thread has been fully or nearly taken up, whereby the needle thread is positively locked while the long waxed loop of thread is drawn back through 10 the work. When however, the take-up starts to set the stitch the thread will be held only by a yielding tension, and this yielding tension is maintained until the stitch has been fully set. It will be noted that the thread 15 pulling movement of the take-up decreases during its take-up stroke. When the downward speed of the end of the take-up is a maximum, the thread remains locked, while the yielding tension is applied when the 20 downward speed is a minimum. This further avoids lashing of the thread at a time when the brake shoe is released and permits a uniform and accurate setting of the stitch. The yielding tension can be accurately adjusted by operating the nuts 35, so as to 25 adapt the machine for different grades of material. This adjustment will not however disturb the operation of the brake shoe.

It will be noted that the thread tension is 30 positioned below and in close proximity to the take-up. This reduces the length of the thread between the truck or roll on the take-up lever and the tension to a minimum. By controlling the thread tension by a lug on 35 the take-up lever, *i. e.*, by means interconnected with the take-up, it is insured that this tension will be operated in accurate time relation with respect to the take-up. The spring 34 causes the thread to be under the 40 tension applied by that spring during the entire cycle of operations of the machine, and the thread is held only under this yielding tension when it is released by the locking means. All these features of construction 45 result in a more accurate operation and action of the thread controlling mechanism, and insure that the lock will be set a uniform distance from the face of the work, irrespective of its thickness, and irrespective of the 50 length of the stitches, and other conditions which may be encountered.

It is obvious that various changes may be made in the details of construction without departing from the spirit of this invention, 55 and it is therefore to be understood that this invention is not to be limited to the specific construction shown and described.

Having thus described the invention what is claimed is:

60 1. In a wax thread sewing machine, the combination with a stitch setting take-up, of a thread tension, and means mounted on and controlled by said take-up for causing said tension to lock the waxed needle thread

against movement while the take-up takes 65 up the thread, and for thereafter causing said tension to hold the needle thread under yielding tension while the take-up sets the stitch.

2. In a wax thread sewing machine, the 70 combination with a stitch setting take-up and a shaft therefor, of a thread tension, and means mounted on said take-up shaft for causing said tension to lock the waxed needle thread against movement while the 75 take-up takes up the thread, and for thereafter causing said tension to hold the needle thread under yielding tension while the take-up sets the stitch.

3. In a wax thread sewing machine, the 80 combination with wax thread stitch-forming mechanism, of mechanism for taking up and setting the stitch, and means controlled by said take-up mechanism for locking the waxed needle thread while the stitch is 85 being taken up, and for thereafter holding the needle thread under yielding tension while the stitch is being set.

4. In a wax thread sewing machine, the 90 combination with a stitch-setting take-up, 90 of a yielding thread tension, a brake operating to brake said tension while the take-up takes up the waxed needle thread, and means operated by said take-up for operating said brake to release the tension while the take-up sets the stitch.

5. In a sewing machine, the combination 100 of a stitch setting take-up member having a thread engaging part, a thread tension separate from said take-up member, means for operating said take-up member to cause said take-up member to take up and set the stitch, and means operating through said take-up member to actuate said thread tension near the end of the take up stroke of 105 said take-up member to relieve the tension on the thread while the stitch is being set.

6. In a sewing machine, the combination 110 of a stitch setting take-up lever having a thread engaging part, a thread tension, and a lug on said take-up lever adapted to engage and actuate said tension near the end of the take up stroke of said take-up member to relieve the tension on the thread while the stitch is being set.

7. In a wax thread leather sewing machine, the combination with a relatively short stitch setting take-up the thread pulling action of which decreases during its take-up stroke, of means for locking the needle 120 thread during the first part of the take-up stroke of the take-up, and for thereafter holding the thread under yielding tension during the last part of the take-up stroke.

8. In a wax thread, lock-stitch, leather 125 sewing machine, the combination with wax thread stitch-forming mechanism, including a hooked needle, and wax applying

means for the needle thread, of means for taking up and setting the stitch, and means for locking the waxed needle thread while the stitch is being taken up, and for there-
5 after holding the needle thread under yielding tension while the stitch is being set, said last means operating to hold the needle thread under such yielding tension at all times during the cycle of operations of the

machine and when the needle thread is re- 10 leased by said locking means.

In testimony whereof we affix our signatures in presence of two witnesses.

GEORGE A. DOBYNE.
